INVENTOR

Frank A. Byram,
By his Attorney,
Wm. E. Powell.

UNITED STATES PATENT OFFICE.

FRANK A. BYRAM, OF PHILADELPHIA, PENNSYLVANIA.

DESIGN FOR TRIMMING.

SPECIFICATION forming part of Design No. 23,886, dated December 25, 1894.

Application filed November 10, 1894. Serial No. 528,425. Term of patent 3½ years.

To all whom it may concern:

Be it known that I, FRANK A. BYRAM, a citizen of the United States, residing at Germantown, (Philadelphia,) in the county of Philadelphia and State of Pennsylvania, have invented a certain new and useful Design for Trimming for Ladies' Underwear, of which the following is a specification.

My invention has for its object the provision of a new and original design for trimming for ladies' underwear of the character fully disclosed by the accompanying drawings, wherein—

Figures 1 and 2 are views of the back and front, respectively, of a portion of such trimming.

My design consists of a wheel-trimming on a chain back, or, in other words, a plain inlay or gimp-like heading backed by three parallel straight rows of chain; a series of pendants or pillars, depending from such heading, each composed of groups or clusters of six single threads in close relation, at their lower ends sustaining another similar row of chain, and having intervening ribbon-spaces; and a row of wheels, supported by the latter through the medium of loops, which wheels are formed of two pieces of yarn at distances apart equal to the diameter of the circles which they are to form, curved outwardly, at intervals, in opposite directions, correspondingly with the curv-

ature of those portions of the wheels which they respectively compose, and doubled or inverted inwardly, toward each other, intermediate, the doubled portions of one piece of 35 yarn overlapping the opposite doubled portions of the other and completing such circles and the respective pieces, in this condition, being backed by four curved rows of chain, whereon they are bound by loops thereof 40 which are thrown around them and appear on the faces of the same, the outermost rows of chain following the contour of the upper and lower portions, only, of the wheels, while the middle or inner rows extend across the openings of the latter and merely touch at the ends of the respective overlapping doubled portions of the yarn which forms the same, at points adjacent to the outer rows, and are drawn together at the centers of each opening by threads, as shown, which, with these chains, form spokes for such wheels.

What I claim as my invention is—

The design for trimming for ladies' underwear substantially as shown and described. 55

In testimony whereof I have hereunto set my hand this 31st day of October, A. D. 1894.

FRANK A. BYRAM.
